UNITED STATES PATENT OFFICE.

GEORGE A. GEMMER, OF MARION, INDIANA.

PUMP-OPERATING MECHANISM.

SPECIFICATION forming part of Letters Patent No. 732,628, dated June 30, 1903.

Application filed May 29, 1902. Serial No. 109,485. (No model.)

To all whom it may concern:

Be it known that I, GEORGE A. GEMMER, of Marion, county of Grant, and State of Indiana, have invented a certain new and useful 5 Pump-Operating Mechanism; and I do hereby declare that the following is a full, clear, and exact description thereof, reference being had to the accompanying drawings, in which like numerals refer to like parts.

10 The object of this invention is to improve the construction of pump-operating mechanism, so as to furnish a support for the pumping-jack, make the device comparatively small, cheap in construction and neat in appearance, and have the parts at the same 15 time convenient for manipulating and controlling the same.

The features of the invention will be understood from the accompanying drawings 20 and the following description and claims.

In the drawings, Figure 1 is a side elevation of the pump-actuating mechanism. Fig. 2 is a side elevation of the actuated end of the bell-crank with connected parts, parts being 25 in section with the bell-crank broken away and showing the position of the parts during actuation. Fig. 3 is the same, showing the position of the parts when the pump is not being actuated. Fig. 4 is a horizontal section 30 on the line 4-4 of Fig. 1. Fig. 5 is a side elevation of the trunnion shown in Fig. 4, one end being broken away. Fig. 6 is an end elevation of the plate connected with the trunnion. Fig. 7 is a plan view of Fig. 2.

35 Referring now to the details, 10 is a stationary platform in which the pump 11 is mounted.

12 is a removable platform secured rigidly to the platform 10 or any other suitable support and carries the major portion of the 40 pump-actuating mechanism.

On the platform 10 in the drawings herein there is mounted an upright gasoline-engine. The particular style of engine is immaterial to this invention and will not be here explained further. On said engine I mount a reducing-gear 15, having near its center a number of holes 16 at varying distances from the center of the wheel in which the connecting-rod 17 is removably mounted and where- 45 by the throw of the connecting-rod 17 may be predetermined and adjusted.

To the platform 12 a fulcrum-plate 18 is se-

cured, carrying a pivot-pin 19, on which the bell-crank 20 is mounted. The actuated arm of the bell-crank extends vertically from the 55 fulcrum and has a horizontally-extending head 21, in which there is a long horizontal slot 22, extending about an equal distance beyond each side of the bell-crank arm. At the middle the head 21 is turned upward to 60 form the extension 23, which contains a short vertically-extending slot 24, that communicates with the horizontal slot 22. The actuating end of the connecting-rod 17 is turned at a right angle to form the pin 25, that extends through the slot 24 and is held up in such slot by a catch 26, that reaches under the pin 25, as shown in Fig. 2. The catch 26 is pivoted to the extension 23 by the pin 27 and has a horizontally-extending weighted handle 70 28 in the form of a bell-crank. The handle 28 holds the catch 26 in engagement with the pin 25, and such catch holds the pin 25 in the slot 24, whereby power is transmitted from the engine to the bell-crank for actuating the latter. When it is desired not to actuate the bell-crank, the handle 28 is thrown upward into the 75 position shown in Fig. 3, which causes the catch 26 to disengage the pin 25 on the connecting-rod and allow said pin to drop down 80 into the horizontal slot 22, in which said pin 25 freely reciprocates during the operation of the engine without actuating the bell-crank. The catch 26 and handle 28 are held out of the way of rod 17 by pin 44. Power 85 is transmitted from the actuating end of the bell-crank 20 to the pump-rod 30 through a pair of bars or links 31 and a trunnion 32. The actuating end of the bell-crank 20 is bifurcated to form the two arms 33, which extend 90 on each side of the pump 11 and by the pins 34 are pivoted to the clips 35, secured to the lower ends of the bars 31, said bars being preferably made of wood. The trunnion 32 has its ends turned round and pivotally 95 mounted in the clips 36, secured to the upper ends of the bars 31. The trunnion is provided with a central vertically-extending recess 45, formed, preferably, by bending the central portion of the trunnion laterally, as 100 appears in Fig. 4. In the recess thus formed the pump-rod 30 fits and is held in said recess in the trunnion by the vertically-disposed clamping-plate 37, which is grooved in the

direction opposite to that of the angle in the trunnion and is clamped to the trunnion by the U-shaped bolt 38 and nuts 39. To hold the parts together firmly, the trunnion is centrally and longitudinally slotted at 40, while the clamping-plate 37 has on each side a central extension 41, that extends through said slot 40, as appears in Fig. 4. Said extensions 41 are horizontally grooved, and there is also a groove 42 in the back of the clamping-plate 37, in which the bolt 38 fits or rests. There is a horizontal extension 43 on each side of both the upper and lower ends of the clamping-plate 37, which extend above and below the trunnion 32. This makes an effectual means for securing the trunnion to the pump-rod, which enables the connection between these two members to be adjusted to suit the pump-rods of varying lengths. In constructing the mechanism the bars 31 are made quite long to accommodate a long pump-rod, and when it is mounted and combined with the pump the bars 31 are cut off and shortened to suit the length of the pump-rod.

25 The advantages of this pump-actuating mechanism are that it is better supported than the walking-beam type, as the support is on the base and very rigid. The mechanism is not bulky and is easily carried and handled. The construction is such that the total cost is comparatively small, and the device possesses a neat appearance. The pumping attachments are such that connection may be made with any pump. Any form or size of pump-rod may be gripped by the trunnion and parts connected therewith, and the thrust is along the center vertical line of the pump-rod, so that there is no side strain.

What is claimed to be the invention, and desired to be secured by Letters Patent, is—

40 1. A pump-operating mechanism including a bell-crank for actuating the pump, a reciprocable rod for actuating the bell-crank, means on one of said parts to guide the movements of the other part when the two are disconnected, and releasable means for connecting said rod with the bell-crank.

2. A pump-operating mechanism including a bell-crank suitably mounted with its driven arm having in it a slot extending substantially at a right angle to said arm, a reciprocating rod for actuating said bell-crank with a pin extending into said slot, and releasable means for connecting said rod to said arm of the bell-crank.

3. A pump-operating mechanism including a bell-crank suitably mounted with one arm provided with a head having in it a long slot and a short slot or notch communicating with the long slot, a reciprocating rod for actuating said bell-crank with a pin extending

through the slot in the head of the bell-crank, and a movable catch pivoted to the head of the bell-crank and adapted when in one position to hold the pin of the actuating-rod centrally in the short slot or notch and when in another position to release said pin and permit it to reciprocate idly in the long slot.

4. A pump-operating mechanism including a bell-crank suitably mounted with one arm provided with a head having in it a long slot extending substantially at a right angle to said arm and a short slot communicating with the long slot or notch and extending at a right angle from the middle of the long slot, a reciprocating rod for actuating said bell-crank with a pin extending through the slot in the head of the bell-crank, a movable catch pivoted to the head of the bell-crank and adapted when in one position to hold the pin of the actuating-rod in the central short slot or notch and when in another position to release said pin and permit it to reciprocate idly in the long slot, and a weight connected with said catch for holding it in engagement with the pin on the actuating-rod.

5. A pump-operating mechanism including a bell-crank suitably mounted with one arm provided with a head having in it a long slot and a short slot or notch communicating with the long slot, a reciprocating rod for actuating said bell-crank with a pin extending through the slot in the head of the bell-crank, a movable catch pivoted to the head of the bell-crank and adapted when in one position to hold the pin of the actuating-rod in the short slot and when in another position to release said pin and permit it to reciprocate idly in the long slot, and a driving-wheel with a number of holes therein located at varying distances from the center thereof in which the actuating-rod may be pivoted.

6. A pump-operating mechanism including a pump-rod, a trunnion with a central vertical groove in it for the pump-rod and having a central longitudinal slot in it, a clamping-plate with a vertical groove in it opposite the groove in the trunnion and a horizontal extension adapted to rest above and below said trunnion, a horizontal groove in the outer surface of said clamping-plate, a U-shaped bolt fitting in said groove and extending through the slot in the trunnion, nuts for tightening said bolt, and means for reciprocating the trunnion.

In witness whereof I have hereunto affixed my signature in the presence of the witnesses herein named.

GEORGE A. GEMMER.
